TWISTER SPINDLE

Ernest Koella, Rockford, Tenn.

Application August 19, 1949, Serial No. 111,167

12 Claims. (Cl. 57—58)

1

This invention relates to improvements in twister spindles of the character used for applying twists to one or more yarns or strands, and particularly relates to the 2-for-1 type of twister spindles.

2-for-1 twister spindles generally, as provided heretofore, have involved a stationary package or yarn support with a rotating flyer and spindle. One turn of twist per revolution is inserted in the yarn between the tension device and the flyer. A second turn per revolution is added between the end of the flyer and the take-up spool.

It has been proposed heretofore to use permanent magnets to hold the yarn carrier against revolving with the spindle but danger was encountered in the use of the magnets in the manner proposed because of a chance of explosion by reason of the magnets releasing their holding action. This explosion results from the release of the yarn carrier which normally is retained in a stationary position, which when released by the magnets would revolve with the main spindle and cause a dangerous wrecking of the equipment due to the centrifugal force which would tear loose the spools on the carrier and cause these to be propelled outwardly with consequent destruction of the mechanism.

One object of this invention is to improve the construction of 2-for-1 twister spindles of the character described, to eliminate the difficulties encountered heretofore, and to provide a safe and effective operating equipment that will provide the desired twist to the yarn in the operation of the spindle.

A further object of the invention is to provide an improved holding action of the fixed magnets on the yarn carrier which will retain the carrier effectively against rotation when desired or provide for rotation in the same or opposite direction from the driving spindle to vary the number of twists imparted to the yarn and the manner in which these are applied.

These objects of the invention may be accomplished by mounting the yarn carrier coaxially of the main spindle and twisted head with provision on the same axis for a magnetic attraction of the yarn carrier either to hold it in a fixed position with respect to the axis and against rotation, or to provide for rotation in the same or opposite direction relative to the main spindle as desired according to the number of twists to be imparted to the yarn. By locating the magnets symmetrically with respect to the axis of the twister spindle and acting in a direction lengthwise of the axis the danger of explosion is minimized or eliminated with respect thereto.

2
inated causing the magnets to act effectively without releasing their hold on the yarn carrier in a more practical and effective manner than if they were placed at the periphery of the twister spindle.

5 The invention is illustrated in different embodiments in the accompanying drawings in which:

Fig. 1 is a vertical sectional view through the twister spindle utilizing the principle of this invention;

10 Fig. 2 is a plan view of the guide ring and magnet holding means taken on the line 2—2 in Fig. 1;

Fig. 3 is a horizontal sectional view there-
15 through on the line 3—3 in Fig. 1;

Fig. 4 is a vertical sectional view through a por-
tion of the spindle of modified construction;

15 Fig. 5 is a plan view of the lower portion thereof on the line 5—5 in Fig. 4;

20 Fig. 6 is a bottom plan view of the upper por-
tion thereof on the line 6—6 in Fig. 4.

The invention is adapted for twisting any de-
25 sired size or character of yarn, of one or more
threads or strands, as the yarn is withdrawn from
a package and delivered to a take-up spool. The
twister spindle illustrated as an embodiment of
this invention is adapted for use in a twister ma-
chine of any desired character only a portion of
which is shown in Fig. 1.

30 A supporting frame on the machine is desig-
nated generally by the numeral 1 in which is
mounted a bearing 2 which constitutes a step-
bearing for supporting therein a main spindle 3.
The spindle 3 extends downwardly through the
step-bearing 2 and has a pulley 4 fixed on the
35 lower end portion thereof in the form illustrated
for operation by the usual belt or band as de-
sired. However, a driving motor may be con-
nected directly with the tubular spindle 3 if
desired.

The spindle 3 is tubular at least in the upper
portion thereof with a central passageway 5
45 through which the yarn may pass to a lateral
discharge opening 6 located within a register-
ing radial opening in a twister head 7. A radial
tube is shown at 8 connected with the opening
in the twister head 7 in radial alignment with
the opening 6. The tube 8 may be straight
50 throughout its length or it may have an up-
turned outer end portion as shown in Fig. 1.

The yarn carrier is designated generally at 9
and includes a hub portion 10 surrounding the
axis of the spindle 3 on which it is mounted on
spaced ball bearings 11 for relative turning move-
55 ment with respect thereto.

Supported upon the yarn carrier 9 at the axis thereof is a tubular member 12 in axial alignment with the spindle 3 forming a continuation thereof. The lower end of the tubular member 12 is fixed securely to the hub 10 whereby this member is in fixed relation to the yarn carrier 9. Orifices 13 are formed in opposite sides of the tubular member 12, one for each strand of yarn to be fed to the spindle, through which orifices the strands or strands of yarn designated generally at Y enter the tubular member 12 and pass into the center passageway of the spindle 3.

The yarn is supported on the usual yarn spools generally designated at 14, two of which are shown in the example illustrated and mounted symmetrically on the yarn carrier 9, being journaled on a central support 15 thereon. Any desired number of yarn supports may be used according to the number of strands to be twisted.

Also mounted on the yarn carrier 9 are eyes 16, one for each strand, which eyes 16 are secured in upstanding sockets 17 supported upon the yarn carrier 9 and are adapted to be adjustably mounted in the sockets by set screws 18 to raise and lower the eyes with respect to the yarn carrier.

Also mounted on the yarn carrier 9 are tension devices 19, one for each strand of yarn, in the path of movement of the yarn from the eyes 16 to the adjacent orifice 13. Each tension device is shown as supported on a bracket 20 secured by a clamp 21 to the upper end portion of the socket 17. The tension devices will provide the required yieldable tension on the yarn as it passes to the tubular spindle.

The yarn passes down through the tubular member 12 and center passage 5 of the spindle 3, thence out through the tube 8 and around the periphery of the yarn carrier 9, which periphery is convex to provide a smooth guiding surface for the yarn. The yarn then passes up over a guide ring 22 mounted above the yarn carrier. The guide ring 22 is supported by radial spokes 23 extending outwardly from a center hub 24 that is secured rigidly on the upper end portion of the tubular member 12.

Arranged in alignment with the tubular member 12 is a second tubular member or support 25 also having a hub 26 mounted on the lower end portion thereof in opposed relation to the hub 24. The tubular member 25 receives the yarn in its lower end from the guide ring 22 and directs it upwardly therefrom on to and over a guide roll 27 supported by the frame 28 of the machine, from which guide roll 27 the yarn passes to a take-up package.

Mounted within the hubs 24 and 26 are opposed horse-shoe magnets 29 and 30 respectively, two of which are shown in each hub. These magnets 29 and 30 are arranged with opposite poles in opposed relation so as normally to tend to attract each other and thereby hold the hubs 24 and 26 together by the magnetic attraction. It is preferred to use an efficient magnetic material for such magnets having a strong magnetic attraction. However, the number of magnets and the size thereof may be varied as desired so as to be effective for the purpose.

The tubular member 25 may be held rigidly in the frame and against rotation if it be desired, thereby to hold the yarn carrier 9 against rotation, or may be mounted for rotary movement either in the same or in the opposite direction to the tubular spindle 3 for varying the number

of twists imparted to the yarn. In the form shown the tubular member 25 is supported by bearings 31 and 32 on the frame 28 which journal this extension for turning movement. A pulley 5 is shown at 33 fixed on the tubular member 25 for rotating the latter, although the pulley may be locked in set position to hold the tubular member against turning movement. This will effect a holding action on the yarn carrier 9 by reason of the connection therebetween through the magnets 29 and 30.

By locating these magnets substantially on the center axis of the spindle the danger of explosion as a result of the operation of the spindle is minimized or eliminated and an effective holding action is accomplished to provide the required twisting of the yarn.

One twist is imparted to the yarn in the tubular portion of the spindle 3 between the tension device 19 and the radial discharge opening 6 while a second twist is imparted thereto as the yarn is discharged through the radial tube 8. This is the action obtained when the tubular extension 25 is held stationary with the yarn carrier. Additional twists may be obtained if desired by rotating the yarn carrier in the opposite direction to the spindle 3.

A modification is illustrated in Figs. 4 and 6 in which tubular spindle portions 12a and 25a are provided respectively with hub portions 24a and 26a that have aligned channels therein to receive the respective magnets 29a and 30a. These magnets are arranged in crossed relation as shown in Figs. 5 and 6 to provide for the use of four magnets in each holding member and thereby obtain an increased holding action. Otherwise this structure operates similar to that described above.

In this way a very simple twister spindle is produced which may be manufactured and used practically without serious danger of explosion as encountered heretofore in twister spindles that use magnetic attraction for holding the yarn carrier. The fastening of the magnet direct to the upper spindle and its extension acts as a magnetic coupling capable of being built up in its magnetic capacity to have a high safety quotient against explosions.

While the invention has been illustrated and described in certain embodiments, it is recognized that variations and changes may be made therein without departing from the invention except as specified in the claims.

I claim:

1. In a twister spindle, the combination of a tubular spindle having an inlet at one portion thereof and an outlet at another portion thereof adapted to receive yarn therethrough, a yarn carrier, means mounting the spindle and yarn carrier for relative turning movement, a tubular member fixed to the yarn carrier, a second tubular member in axial alignment with the tubular member, and magnets in opposed relation and connected with said tubular members forming a magnetic attraction therebetween.

2. In a twister spindle, the combination of a tubular spindle having an inlet at one portion thereof and an outlet at another portion thereof adapted to receive yarn therethrough, a yarn carrier, means mounting the spindle and yarn carrier for relative turning movement, a tubular member fixed to the yarn carrier substantially coaxially of the tubular spindle, a tubular extension in longitudinal alignment with the tubular member, and means forming a magnetic attraction be-

tween the tubular member and the extension for holding the yarn carrier against rotation with the tubular spindle.

3. In a twister spindle, the combination of a tubular spindle having an inlet at one portion thereof and an outlet at another portion thereof adapted to receive yarn therethrough, a yarn carrier, means mounting the spindle and yarn carrier for relative turning movement, a tubular member fixed to the yarn carrier and extending upwardly therefrom substantially in longitudinal alignment with the tubular spindle, a hub fixed on the upper end portion of said tubular member, a tubular extension mounted in longitudinal alignment with the tubular member, a hub on the lower end portion of said tubular extension, magnets mounted in the hubs in opposed relation to each other in positions to form a magnetic coupling between the tubular member and the extension.

4. In a twister spindle, the combination of a tubular spindle having an inlet at one portion thereof and an outlet at another portion thereof adapted to receive yarn therethrough, a yarn carrier, means mounting the spindle and yarn carrier for relative turning movement, a tubular member fixed to the yarn carrier and extending upwardly therefrom substantially in longitudinal alignment with the tubular spindle, a hub fixed on the upper end portion of said tubular member, a tubular extension mounted in longitudinal alignment with the tubular member, a hub on the lower end portion of said tubular extension, magnets mounted in the hubs in opposed relation to each other in positions to form a magnetic coupling between the tubular member and the extension, and means journaling the tubular extension for rotary movement.

5. In a twister spindle, the combination of a tubular spindle having an inlet at one portion thereof and an outlet at another portion thereof adapted to receive yarn therethrough, a yarn carrier, means mounting the spindle and yarn carrier for relative turning movement, a tubular member fixed to the yarn carrier and extending upwardly therefrom substantially in longitudinal alignment with the tubular spindle, a hub fixed on the upper end portion of said tubular member, a tubular extension mounted in longitudinal alignment with the tubular member, a hub on the lower end portion of said tubular extension, magnets mounted in the hubs in opposed relation to each other in positions to form a magnetic coupling between the tubular member and the extension, and means for guiding the yarn from the tubular spindle into the lower end of the tubular extension for upward passage therethrough.

6. In a twister spindle, a tubular spindle having a passageway therethrough adapted to receive yarn in one portion thereof and to direct the yarn out of another portion thereof, a yarn carrier, means mounting the tubular spindle and yarn carrier for relative rotation, a tubular member secured to the yarn carrier in axial alignment with the tubular spindle and having an inlet opening therein for the yarn, package support means on the yarn carrier, an eye supported by the yarn carrier adapted to receive the yarn from the package, and a tension device supported by the yarn carrier between the eye and the inlet opening.

7. In a twister spindle, a tubular spindle having a passageway therethrough adapted to receive yarn in one portion thereof and to direct the yarn out of another portion thereof, a yarn carrier, means mounting the tubular spindle and

yarn carrier for relative rotation, a tubular member secured to the yarn carrier in axial alignment with the tubular spindle and having an inlet opening therein for the yarn, package support means on the yarn carrier, an eye supported by the yarn carrier adapted to receive the yarn from the package, a tension device supported by the yarn carrier between the eye and the inlet opening, a socket mounted on the yarn carrier, means adjustably supporting the eye in the socket, and means mounting the tension device on the socket.

8. In a twister spindle, a tubular spindle having a passageway therethrough adapted to receive yarn in one portion thereof and to direct the yarn out of another portion thereof, a yarn carrier adapted to support a package, means mounting the tubular spindle and yarn carrier for relative rotation, an eye mounted on the yarn carrier adapted to receive the yarn from the package, a tension device supported by the yarn carrier between the eye and the tubular spindle, a socket mounted on the yarn carrier, means supporting the eye in the socket, and means mounting the tension device on the socket.

9. In a twister spindle, the combination of a tubular spindle having an inlet at one portion thereof and an outlet at another portion thereof adapted for passage of yarn therethrough, a yarn carrier, means mounting the spindle and yarn carrier for relative turning movement, a guide for the yarn spaced axially of the spindle from the outlet thereof, and means for holding the yarn carrier against rotation with the spindle including opposed magnets spaced from the spindle adjacent the opposite end thereof from the outlet.

10. In a twister spindle, the combination of a tubular spindle having an inlet at one portion thereof and an outlet at another portion thereof adapted for passage of yarn therethrough, a yarn carrier, means mounting the spindle and yarn carrier for relative turning movement, a guide for the yarn spaced axially of the spindle from the outlet thereof, and means for holding the yarn carrier against rotation with the spindle including opposed magnets spaced lengthwise of the spindle axis adjacent the opposite end of the spindle from the outlet.

11. In a twister spindle, the combination of a tubular spindle having an inlet at one portion thereof and an outlet at another portion thereof adapted for passage of yarn therethrough, a yarn carrier, means mounting the spindle and yarn carrier for relative turning movement, a guide for the yarn spaced axially of the spindle from the outlet thereof, and means for holding the yarn carrier against rotation with the spindle including opposed magnets having poles symmetrically arranged on different sides of the spindle, said magnets being mounted adjacent the guide and spaced lengthwise at the opposite end of the spindle from said outlet.

12. In a twister spindle, the combination of a tubular spindle having an inlet at one portion thereof and an outlet at another portion thereof adapted for passage of yarn therethrough, a yarn carrier, means mounting the spindle and yarn carrier for coaxial turning movement relative to each other with the outlet of the spindle at one side of the yarn carrier, a guide for the yarn spaced axially of the spindle on the opposite side of the yarn carrier from the outlet, and means for holding the yarn carrier against rotation with the spindle including opposed magnets spaced

from the spindle adjacent the opposite end thereof from the outlet.
